TWO-DECKER BED

Ervin F. Kurth, United States Army, Washington,
D. C., and Eugene Le Roy Briggs, High Point,
N. C.

Application July 9, 1942, Serial No. 450,314

2 Claims. (Cl. 5-8)

This invention relates generally to beds and particularly to beds that can be used as single beds or be set one on top of the other to form a two-decker bed.

An object of this invention is to provide a novel form of means for assembling the members of the bed frame, the assembling means being such that while thoroughly effective for holding the parts rigidly together such parts may be readily separated or detached if it is desired to take the bed down.

Another object of the invention is to form one or two beds, one above the other, thus permitting of having two beds in the space at present occupied by a single bed.

The present invention is designed more particularly for use in army camps but it can also be found advantageous for use in hotels, summer houses, on transport and hospital ships or in other places where space is at a minimum.

This bed was primarily designed for its simplicity, cheapness, lightness, durability and the obviation from all danger of collapse while in use, and for the further reason that loose or spare parts will be eliminated when this bed is used as a single or a two-decker.

While from a standpoint of vital materials it is preferred to construct the frame of wood, it is to be understood that the invention is not to be limited to the employment of this material, as it will be obvious that, if preferred, the same ideas may be carried into effect by making the frame of metal or other suitable materials.

With these and other objects in view, as will appear, the invention consists of the novel construction and combination of parts of a single or two-decker bed, as will be hereinafter fully described and claimed.

In the accompanying drawings, forming a part of this specification, and in which like numerals of reference indicate corresponding parts, there is illustrated a form of the embodiment of the invention, which embodies the essential features thereof. It is also to be understood that these may be departed from in various details of construction and proportions of parts without departing from the spirit of the invention, and in the drawings:

Fig. 1 is a side elevation of the invention in use as a single bed.

Fig. 2 is a similar view as a two-decker bed.

Fig. 3 is an end view of Fig. 1 looking in the direction of the arrow.

Fig. 4 is a similar view of Fig. 2.

Fig. 5 is a fragmentary sectional view of the means for assembling the frame of the bed.

In the form of bed herein shown, there are presented two tiers or beds divided by a central rail into two separate bed sections, the occupant of the upper bed being prevented from interfering with the occupant of the lower bed by means of a central rail.

Referring to the drawings in detail, 10 and 11 designate the head and foot sections of the bed 12. In Fig. 1 the head section 10 is used when the bed is to be used as a single bed; likewise the foot section 11; but when the bed is to be used as a two-decker, as shown in Fig. 2, the bed 13 will utilize two head sections 10 and the bed 14 will utilize two foot sections 11. This is done to give the occupant of bed 13 sufficient head room and air space and to prevent interference of the occupant of the upper bed with the occupant of the lower bed.

Referring more particularly to the head section 10 which in this instance is composed of two corner posts 15 secured together by any well-known means, (such as dowels D) by braces 16 and a top board 18 at points 17, the top board is designed to project above and beyond the corner posts 15 as shown at 19. This is done in order that the top board 18 can fit into a transverse groove 20 formed at the bottom of the corner post 21 of the foot sections 11. The foot section 11, like the head section 10, is composed of two corner posts 21 secured together by any well-known means, (such as dowels D) by braces 22.

The head and foot sections 10 and 11 respectively are joined together by side rails 23 having slats 24 rigidly secured thereto. The rails 23 are joined together by side rails 25 which are adapted to rest on blocks 26 secured to the corner posts 15 and 21. This construction forms a frame which can be moved as a unit and thus less time is required to assemble the bed as a single or two-decker.

In Fig. 5 where the foot sections 11 are taken as an illustration, the means for joining the frame composed of side and end rails 23 and 25 respectively is more specifically shown, as is also shown the corner block 27, which is placed in the corner of the frame and held in position by nails N. The corner block 27 strengthens the frame and prevents it from moving or shifting out of shape.

The bolt 28 is inserted through the post 21 in a suitable opening but is screwed into the end rail 25 and the side rail 23. When the bolt 28 is screwed into the side rail 23, it will engage a nut

31 which has been inserted into the side rail 23 through mortise 32. A nut 29 is then threaded on to the bolt 28 and tightened. This will clamp the bed together to form a strong and rigid construction, since the nut 31 will prevent the nut 29 from withdrawing the bolt 28 from the side rail 23. Dowels, not shown, are placed on either side of the bolt 28 to prevent the side rails 23 from twisting or shifting out of place. A circular recess 30 is counterbored in the post 24 in order that the nut can sink into the post and thus present a neater appearance as well as omit any projections on which to catch bed clothing or garments.

It will be seen from the foregoing description that while the device of the present invention is of exceedingly simple construction, it will be thoroughly efficient and durable in use and by reason of the manner in which the parts are associated the danger of breakage or disarrangement in use will be reduced to a minimum.

From the foregoing it is thought that the construction, operation and many advantages of the herein-described invention will be apparent to those skilled in the art without further description and it will be understood that various changes in the size, shape, proportions and minor details of construction may be resorted to without departing from the spirit or sacrificing any of the advantages of the invention.

Having thus described the invention, what is claimed as new and desired to secure by Letters Patent is:

1. In a double deck bed, the combination of a lower bed having head and foot sections of uniform height and having upwardly projecting corner-posts on each section, said sections each including a board-like member connecting and projecting above the corner posts, and an upper bed having end sections including corner posts substantially shorter than the posts of the lower bed and having transversely slotted feet, the posts of the upper bed resting on the posts of the lower bed with the projecting member entering the slots, all the head and foot sections having detachable connecting means at uniform distances from the lower ends of their corner posts, said 10 board-like members forming headboards for the beds, whereby the beds are capable of being reassembled as separate beds, each having a high head section and a low foot section.
2. A bed having a removable head section having corner posts and a headboard projecting above said posts and a removable foot section having corner posts substantially shorter than those of the head section and having transversely slotted feet, whereby the bed may be reassembled in combination with another similar bed to form 15 a double deck bed, with both of the end sections having headboards on the lower bed and the other bed placed on top with its slotted feet engaging the headboards.
